UNITED STATES PATENT OFFICE.

ELMER LEE, OF BANGOR, PENNSYLVANIA.

DEVICE FOR HOLDING FRUIT-JARS.

964,978.

Specification of Letters Patent. Patented July 19, 1910.

Application filed March 9, 1910. Serial No. 543,182.

To all whom it may concern:

Be it known that I, ELMER LEE, a citizen of the United States, residing at Bangor, in the county of Northampton and State of Pennsylvania, have invented a new and useful Device for Holding Fruit-Jars, of which the following is a specification.

It is the object of the present invention to provide an improved device for holding fruit jars during the filling and sealing 10 operation.

Owing to the fact that the food stuffs to be preserved are introduced into the jar while in a highly heated condition, it has 15 heretofore been necessary to grasp the jar with a cloth which usually is saturated with water prior to use. It is difficult, however, to hold a jar against turning, under these conditions, when the top is being applied, 20 and the present invention therefore aims to provide a device in which the jar may be firmly clamped during the filling and sealing operations, and also when it is desired to remove the lid and which may be applied 25 to any ordinary table.

The invention further aims to so construct the device as to adapt it to clamp jars of various sizes.

In the accompanying drawings,—Figure 30 1 is a perspective view of a jar holding device constructed in accordance with the present invention. Fig. 2 is a sectional view therethrough on the line 2—2 of Fig. 1, and Fig. 3 is a perspective view of one of a 35 number of filling members employed in connection with the device.

In the drawings, the device is illustrated as embodying a frame comprising side members 5 connected in spaced relation by a 40 semi-annular web 6 integral therewith. The said web 6 is located in a plane between the upper and lower ends of the side members 5 and the extremities of the web overlie the forwardly right angularly extending lower 45 ends 6' of the side members 5. Clamping screws 7 are threaded through the angular lower ends 6' of the said members 5 and at their upper ends are provided each with a swiveled bearing head 8. In applying the 50 device to a table or the like, it is disposed thereon with the edge of the table top received between the said projecting extremities of the web 6 and the bearing heads 8 after which the clamping screws are tightened. The upper ends of the members 5 are 55 also formed to extend forwardly at right

angles, as at 9, and these portions 9 overlie the respective extremities of the web 6.

The jar clamping device proper includes a fixed clamping member and a movable 60 clamping member, and of these two members the fixed member is indicated by the numeral 10, it being semi-cylindrical in form and provided at each end with an ear 11. This fixed member is disposed between the portions 9 of the side members 5 with its ears 11 resting upon the upper faces of the said portions and securing screws 12 or rivets are engaged through the said ears and into the said portions 9. It will be observed that the 70 concave side of the fixed member 10 is presented inwardly. The movable member is indicated by the numeral 13 and is also semi-cylindrical in form and is pivoted at one end, as at 14, by means of an ear similar to 75 one of the ears 11 of the member 10 to the forward end of one of the said portions 9. At its end opposite that end at which the ear 14 is formed, the said member 13 is provided or formed with an ear 15 which is, 80 however, not secured to the corresponding portion 9 although it rests thereon and is movable thereover. This said portion 9 extends forwardly to a greater distance than does the other said portion and swiveled 85 upon the same at the forward end thereof is a clamping cam lever, of which the body is indicated by the numeral 16 and the handle by the numeral 17. The edge of the body of the cam engages against the forward edge 90 of the said ear 15 and when the cam is swung around in one direction, the member 13 will be forced into clamping relation with respect to the member 10, as will be readily understood.

From the foregoing description it will be readily understood that if a large jar is to be filled, it is disposed bodily between the members 10 and 13, after which the cam lever is swung so as to bring the member 13 into 100 clamping relation with respect to the member 10 which will result in the jar being firmly held with its bottom resting upon the surface of the table and its mouth uppermost to permit of it being easily filled. It 105 will be understood that the jaw top or cap may be readily and conveniently applied or removed while the jar is thus securely held by the device and that this application of the top may be accomplished without danger of 110 burning one's hands or cutting due to breaking of the jar. Inasmuch as it is frequently

desirable or necessary to fill several sizes of jars in one preserving and canning operation, it is expedient that means be provided whereby the device may be adapted 5 to clamp jars of various sizes and this means is embodied preferably in a number of sectional bushings, each section of which is semi-cylindrical in its body portion 18 and is provided at the upper end of its said body 10 portion with a semi-annular flange 19, which flange projects from the convex side of the said body. These bushings are preferably made of fiber also with rubber covering on fiber and are so relatively proportioned as 15 to fit one within another when their sections are properly assembled. The employment of a majority of the bushings adapting the device to clamp a small jar and the employment of a minority of the said bushings 20 adapting the device to clamp a large jar. It will be observed that the sections of the several bushings are disposed in a concavity of the members 10 and 13 with their flanges resting either upon the upper edges of the 25 said members or upon the flanges of corresponding enveloping sections. In order to hold the sections of the bushings in proper assembled relation, the sections 10 and 13 are formed with lugs or projections 20 at a point 30 substantially midway between their ends and upon their convex sides and upstanding from

each of these lugs is a pin 21 fitting in openings 22 which register in the superposed bushing sections.

What is claimed is:—

35 1. In a device of the class described, a fixed clamping member, a clamping member movable into and out of clamping relation with respect to the fixed member, and a bushing removably fitted between the said 40 members, and means whereby the members last mentioned may be moved to clamping position, the said bushing comprising a pair of sections one fitted in each of said clamping members.

45 2. In a device of the class described, a fixed clamping member, a clamping member movable into and out of clamping relation with respect to the fixed member, means whereby the said member may be so moved, 50 a pin upon each of the said clamping members, and nested bushing sections carried by each of the clamping members and having registering openings receiving the respective pin.

55 In testimony that I claim the foregoing as my own, I have hereto affixed my signature in the presence of two witnesses.

ELMER LEE.
